Elihu Smith of Albany N. Y.
Letters Patent No 5.11 Dated Oct 19th 1852

The schedule referred to in these Letters Patent and making part of the same

Be it known that I, Elihu Smith of the City of Albany
have produced an ornamental Design for a Cooking Stove (which stove I call
"Pride of our Union") and I do declare that the annexed accompanying draw-
ings are full & accurate delineations of the ornamented parts with their several or-
naments. The side plate and end plate of the elevated oven not shewn being
similar to those shewn & symmetrically ornamented.

That I claim as my production and desire to secure by
Letters Patent is the combination & arrangement of ornamental figures & forms
represented in the accompanying drawings forming together an ornamental Design
for a Cooking Stove.
